Sellars Patent

The defendant referred to in their Sellars Patent and the king part of the same con-
cerning a description in the words of the said James Apple himself of his improve-
ment in the new lock in addition to those for which a patent was granted him
in the 1st May 1832.

To all whom it may concern. Be it known, that James Apple of Ramapo in the County
of Rockland and State of New York did make certain improvements in the old lock
intended for Boxes of Banks and if the place is in great security is required for
such improvements Sellars Patent of the United States was granted with the
on the eighteenth day of May in the Year one thousand eight hundred and
thirty two, and that same had since been further improved the said lock
and have thereby rendered it more efficient and secure in its operation and
I do hereby declare that the following is a full and exact description of these
improvements referred to in the drawings which accompany this specific
cation and make part thereto. In the frame of this lock A A big plate
contains the bolt and its appendages as are herein given. The plate B B which
is the outer plate upon the door is in one piece covering the whole of the
box or frame. The Two Arms C C and the other Arms D D rise from the plate A to which
they are firmly joined being usually cast in one piece than with they stand up
the whole thickness of the bolt to which they serve as guides and they also serve
the cap plate C and D which are to be secured on them.

The bolt D which may be made to draw and may be made and
in the same direction as is to be turned down in from time to throw out and in
several directions as is pointed at E in the manner of my former lock; but performed
a mark in like manner continuing within it to number or name D by which the bolt
is to be moved backward and forward. At the back end the bolt is cut off into
two, leaving an open space between them as seen in the drawing. In the same
line of end of these branches turn on their grana. 112 extending down through
the whole depth of the bolt, and there is between a single grana a notch 13 of

the outer end of each of these two bars is formed into a hook, the head of which projects out from the body of the bar; along each of these edges is a serrated edge to the depth of the piece of metal, and which may be one-twelfth of an inch wide or less in thickness. The use of these flanchers will be presently described. The end of the bar is used by means of a small arched projection, which is caused to hold the bolt when they are held by the key, and having on any other member of the lock, being usually made of steel plate in the general form of that shown in Fig. 1, and is fastened to these jaws in such a small capacity as to diminish the weight of the lock.

When four projecting bars when they are placed between the guides shown in Fig. 1 are passed by them and fall into or are received by the jaws of the guides the lock is disengaged. The four bars being so arranged that the jaws of the key lie upon which the cases or lifters are placed, in a way much like that described in my first patent. However usually, except the opening in these cases or lifters, ignorant in any other form by which they will be released from the projections when dropped upon the jaws or shank of the key.

There are shown separately at N. N. and the number which they are fixed at. The slopes of the opening to may be varied in any way so that it admits the key to act properly upon the neck pieces. These pieces being here but one projection or more have no projections at each end the bolt being caused accordingly to receive them, it generally makes the cases or lifters N. N. of equal length and also of different thicknesses and form a set from a correspondence with each case or lifter; referring to insuring the corresponding pieces in order that they may be readily placed to admit to a correspondence with each other; the methods of correspondences of which these pieces are designed may in either of these ways be easily readily explained. Fig. 5 is a transverse section of the bolt through the guides in which the neck pieces pass, and also through the pieces themselves. This section which is also the flancher previously named projecting from the outer end of the bolt which is a flange passing through the flancher & may be used to secure the bolt, but for the purpose to which it is intended need only to apply this lock or employ only a short piece of steel projecting through the plate of the lock which is attached to the door key. The kind of key which may be used to set up on the handle and turn the bolt with the form which may be given to the piece which is to pass over the stem P are shown in Fig. 6. This lock

so to the door through holes in the plates. Fig. 1 shows the plates
and lock in a upright position. The lock, which is then put on in such a way that it
cannot be removed without the assistance of the key, is shown. Fig. 2 shows a view
of one of the pieces of metal which is the key, illustrating the principle and
construction of the lock. The best and most simple of these pieces are projecting hook
pieces upon the blade, A, which hook pieces pass through the notch, B, in the back of
the lock and catch under the plates open to a key. A piece of metal, C, is
also projecting from the plate, B, which piece is connected or joined to each end and
falls into a slot corresponding with it on the bolt, D, in the case of the key or from
the lock at its front end. When this is slipped into its place, the hook pieces are
not pulled through the slot but extend to about half its full distance
and it would therefore be brought into this position to enter the notch, B.

To prevent all motion in the plate when in its
place a screw is passed through the back end of it into the stand, E. Fig. 1 shows this
arrangement—the lock cannot be removed from the door on the inside without the
use of both the key and also make the box which receives the bolt to sink a body, the
it cannot be removed from the door post when the door is closed. The screw in this
case, as shown in Fig. 2, is a plate which is fastened on and which has
decreased or otherwise formed grooves at each end. The box post, F, fits into these
grooves and covers the door handle. This box post is then attached to the blade, G, by the
means the screw of which, however, will not admit of the box being removed with
out passing the door. When the bolt is in the proper place the not pieces fall
into their corresponding grooves by their own gravity but should they not do so
readily the action of the key upon them will force them forward which was not the
case with the locks formerly used by me.

That I claim as constituting the improvements for which I am
claim a patent to the use of the pieces which I designate the lock of the lock the
the different positions of which they are susceptible when not operating upon
the principle described, which it does not consist of combination with that of the lock
a my former patent, I also claim the attaching of the metal plate to the lock by means
which prevent its being detached without the agency of the key and the attacking
of the door upon the bolt so that it cannot be removed while the door is closed.
